UNITED STATES PATENT OFFICE.

ALFRED F. LA SHELLS, OF BIGGS, CALIFORNIA.

REVOLVING PLOW.

SPECIFICATION forming part of Letters Patent No. 356,284, dated January 18, 1887.

Application filed November 3, 1886. Serial No. 217,916. (No model.)

To all whom it may concern:

Be it known that I, ALFRED F. LA SHELLS, of Biggs, Butte county, State of California, have invented an Improvement in Revolving Plows; and I hereby declare the following to be a full, clear, and exact description of the same.

My invention relates to that class of revolving plows in which a rotating head or cylinder is provided with suitable plow bottoms or shares; and my invention consists in the head or cylinder provided with the series of spirally-arranged separate or individual plow bottoms, shares, or blades hereinafter fully described.

My invention further consists of said head with its shares in connection with a suitable wheeled frame, upon the rear end of which it is mounted, and power-transmitting mechanism by which it is rotated, the power being derived either from an engine on the frame, which also causes the progression of the machine, or from draft-animals through traction, all of which I shall hereinafter fully explain.

The object of my invention is to provide a simple and effective revolving plow.

Referring to the accompanying drawings for a more complete explanation of my invention, Figure 1 is a plan of my machine. Fig. 2 is a view of the cylinder with its plowshares. Fig. 3 is a perspective view of one of the plowshares. Fig. 4 is a detail of the steering mechanism.

A is a frame mounted upon wheels B, and having the steering-wheel *b* in front.

C is an engine upon the frame, from the driving-shaft of which a belt, *c*, extends to a pulley, *d*, on a counter-shaft, D, mounted transversely on the frame. Upon said shaft are pulleys *d'*, from which belts E extend to pulleys *e* on the axles of the main wheels B of the machine, whereby the progression of said machine is effected.

F is a cylinder-head, the central shaft, *f*, of which is mounted on the rear of the frame, and has pulleys *f'*, from which belts *f''* extend to the pulleys *d'* on the counter-shaft D, whereby rotation is imparted to said cylinder-head.

G are the plow bottoms, shares, or blades, mounted upon the cylinder-head by means of suitable braces or arms, *g*. These plowshares

are of a diamond or rhomboidal shape, as shown in Fig. 3, their faces being concave. They are arranged upon the cylinder-head at about the angle shown and in several series in a spiral course, like the multiplex thread of a screw, corresponding plows in each series being in the same vertical planes. Those in each series are placed close enough together that their vertical planes transversely through the head are practically continuous by coming close together, and the vertical longitudinal planes of the ends of each series lie close to the vertical planes of the preceding and succeeding series, whereby, though the plows are separated and are individual shares, they as a whole approximately cover the area over which they pass.

It is obvious that, instead of belts for transmitting motion to the cylinder-head, I may use gears, if found preferable.

The operation of the machine is as follows: By means of the engine the progression of the machine is effected, and at the same time direct power is transmitted to rotate the cylinder-head forwardly, so that its plowshares travel in the direction of the travel of the machine. The plowshares are so arranged upon the cylinder-head that in moving forward and then downwardly they take the ground with their foremost points and cut it, and as they cut they turn the earth over completely. This movement and the resistance which the ground affords, instead of impeding the progress of the machine, serve to assist it in the same manner as the paddle-wheel of a stern-wheel steamer. The plows, being individual separate shares, cut the ground at short distances, thus preventing the formation of the large lumps which are left by the ordinary drag-pow method. In this latter method, when the ground is at all sticky, it is obvious that as the single share advances in a direct line the ground which is turned over to one side by the mold-board may and does adhere for a greater or less distance, and when dry it forms a large and solid clod; but with my plow this is obviously not the case, for the plows in the same vertical plane succeed each other at such short distances that the ground is cut into small pieces, and each piece turned over by the plows as they succeed each other, thus avoid-

ing all clods and making straight parallel furrows.

My machine should not be confounded with harrows and cultivators in which rotating cylinder-heads are provided with harrow-spikes or cultivator blades or teeth. These machines simply scratch the ground, and do not in any sense plow it; nor can they be used for the purpose of plowing. My shares are perfect plows in their construction and operation, and they accomplish the true work of plowing—namely, the cutting and complete turning over of the earth. Their operation is the reverse in direction to that of the ordinary drag-plow, as they take and cut the ground from above backwardly, while the ordinary plow takes the ground from underneath and forwardly, and is therefore, what its name implies, a drag or resisting influence to the progress of the machine or implement; but, as I have before stated, my plows rather accelerate than impede the machine. It will also be seen that the direction of plowing is in the direction of travel of the machine, and in this it differs from those other revolving plows in which the shares travel on an endless belt and at right angles to the course of the machine.

I do not confine myself to the employment of a solid cylinder-head such as I have here shown, for I may make it of a lighter construction, as by the employment of independent hubs or rims keyed upon a common shaft and each carrying its complement of plowshares. Nor do I confine myself to the employment of a steam-engine for operating the

cylinder-head and for advancing the machine, as I may derive the power for rotating said head from the traction of the wheels, effecting the progress of the machine itself by horses or other draft animals.

In Fig. 4 I show the means I would employ for steering the machine. The spindle b' of the wheel is provided with a worm-gear, b^2 , on its top, with which meshes a worm-gear, b^3 , operated by a crank-wheel, b^4 .

Having thus described my invention, what I claim as new, and desire to secure by Letters Patent, is—

1. In a revolving plow, the wheeled frame and an engine by which its progress is effected, in combination with the cylinder-head mounted on the rear of the frame, power-transmitting mechanism from the engine by which said head is rotated, and the series of spirally-arranged separate or individual plow bottoms or shares carried by said head, substantially as herein described.

2. In a revolving plow, the rotating cylinder-head, in combination with the diamond-shaped or rhomboidal concave-faced plow-shares and the bent braces or arms by which said shares are secured at the proper angle to the cylinder-head, substantially as herein described.

In witness whereof I have hereunto set my hand.

ALFRED F. LA SHELLS.
